UNITED STATES PATENT OFFICE.

WILLIAM F. SIEGENER, OF PHILADELPHIA, PENNSYLVANIA, ASSIGNOR TO
HERRMAN DIENELT, OF SAME PLACE.

DESIGN FOR SHELF-PAPER.

SPECIFICATION forming part of Design No. 34,986, dated August 20, 1901.

Application filed July 29, 1901. Serial No. 70,186. Term of patent 3½ years.

To all whom it may concern:

Be it known that I, WILLIAM F. SIEGENER, a citizen of the United States, residing in Philadelphia, Pennsylvania, have invented and produced a certain new and original Design for Shelf-Paper, of which the following is a specification.

My design, which relates to the ornamental border of the shelf-paper, is shown in the accompanying drawing, which represents sufficient of the pattern to illustrate the design, the remainder of the pattern being merely a repetition of what is shown.

The design comprises as its essential features certain rows of perforations and perforated figures adjacent to the scalloped edge of the paper.

1 represents a scalloped edge, and 2 represents a row of circular perforations some distance inwardly from the scalloped edge. Between this row of perforations and the scalloped edge are shown three rows of figures 3, forming the balance of the design. The fig-

ures 3 are substantially square in general outline, being made up of a central circular 25 perforation, with wedge-shaped perforations on four sides of said square figure and projecting toward the central perforation, while at the corners of the figures perforations formed of three joining segments of different 30 diameters are shown. Inside the scalloped edge is a curved row 4 of wedge-shaped perforations following the contour of said edge.

Having thus described my invention, I claim and desire to secure by Letters Patent—

The design for shelf-paper substantially as described and as shown in the accompanying drawing.

In testimony whereof I have signed my name to this specification in the presence of two subscribing witnesses.

WM. F. SIEGENER.
